UNITED STATES PATENT OFFICE.

ELLWOOD C. JOHNS, OF JERSEY CITY, NEW JERSEY, ASSIGNOR TO GOLD CAR HEATING & LIGHTING COMPANY, OF NEW YORK, N. Y., A CORPORATION OF NEW YORK.

DESIGN FOR A CASING FOR THERMOSTATS.

50,787.

Specification for Design.

Patented May 15, 1917.

Application filed March 2, 1917. Serial No. 152,133. Term of patent 14 years.

To all whom it may concern:

Be it known that I, ELLWOOD C. JOHNS, a citizen of the United States of America, residing at No. 211 Myrtle avenue, Jersey City, in the county of Hudson and State of New Jersey, have invented a new, original, and ornamental Design for a Casing for Thermostats, of which the following is a specification, reference being had to the accompanying drawing, wherein—

Figure 1 is a front elevation.

Fig. 2 is a side elevation, the general design being drawn only at the top and bottom thereof, and the part omitted corresponding to that shown, and a portion of the side being cut away to better show the design of surface ornamentation.

Fig. 3 is a top view; and

Fig. 4 is a bottom view, not completely drawn, the part omitted corresponding to that shown, which shows the general design as it appears from the bottom.

I claim—

The ornamental design for a casing for thermostats, as shown.

In witness whereof, I have hereunto signed my name in the presence of a subscribing witness.

ELLWOOD C. JOHNS.
